UNITED STATES PATENT OFFICE

95,825

DESIGN FOR A SANDING MACHINE

**Theron L. Hedgpeth, Oak Park, Ill., assignor to
Duro Metal Products Company, Chicago, Ill.,
a corporation of Illinois**

Application March 6, 1935, Serial No. 55,754

Term of patent 14 years

To all whom it may concern:

Be it known that I, Theron L. Hedgpeth, a citizen of the United States, residing at Oak Park, in the county of Cook and State of Illinois, have invented a new, original, and ornamental Design for Sanding Machines, of which the following is a specification, reference being had to the accompanying drawing, forming part thereof.

The figure is a view in perspective of a sanding machine embodying my design.

I claim:

The ornamental design for a sanding machine as shown.

In witness whereof I hereunto subscribe my name, this 26th day of February, 1935.

HERON L. HEDGPETH.
